(57) **CLAIM**

The ornamental design for a multi-surface mount for a display panel, as shown and described.

DESCRIPTION

FIG. 1 is a top perspective view of a multi-surface mount for a display panel;

FIG. 2 is a top perspective view thereof, shown in an environment of use;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof;

FIG. 8 is a bottom plan view thereof; and,

FIG. 9 is a left elevation view thereof, shown in an environment of use.

The broken lines shown in FIGS. 1 and 3-8 illustrate portions of the multi-surface mount for a display panel that form no part of the claimed design. The broken lines illustrating the display panel and surface in FIGS. 2 and 9 are environment, while the remaining broken lines in FIGS. 2 and 9 illustrate portions of the multi-surface mount for a display panel that form no part of the claimed design.

1 Claim, 9 Drawing Sheets
